His Attorney.

UNITED STATES PATENT OFFICE.

FRANK N. SPELLER, OF PITTSBURGH, PENNSYLVANIA.

WATER-DEACTIVATING APPARATUS.

Application filed May 16, 1927. Serial No. 191,718.

This invention relates to water deactivating apparatus and has for its object the provision of an improved apparatus of this class in which finely divided ferrous or other corrodible metal is used as a deactivating material.

A further object is to provide an apparatus of this class in which the deactivating metal may be readily charged and discharged by ordinary or unskilled labor.

Other objects and advantages will be brought out in the following specification.

In the drawings—

Figure 1 is a vertical sectional view through a deactivating apparatus constructed in accordance with my invention.

Figure 2 is a top plan thereof.

Figure 3 is a bottom plan thereof.

Referring more particularly to the drawings, the numeral 2 designates the deactivating tank shell which has a head 3 and bottom 4 riveted or otherwise secured therein. The head 3 is provided with a manhole opening 5 through which the deactivating metal is charged. A manhole closure or plate 6 is provided for normally closing the opening 5 and is adapted to be locked in closed position by a yoke 7 carried on a bolt 8 and a nut 9, which is threaded on the bolt 8 and adapted to be screwed down against the yoke 7 to draw the plate 6 tight against the head 3.

The bottom 4 is provided with a discharge opening 10 for the used or spent deactivating metal, which opening is normally closed by a hinged cover or plate 12. The plate 12 is provided with slotted ears 13 at spaced intervals around its periphery which fit around or over hook-shaped lugs 14 when the cover plate is in closed position and wedges 15 are adapted to be driven home between the hooked ends of the lugs 14 and the ears 13 to lock the plate in closed position.

A sectional frusto-conical grid 16 is mounted in the lower end of the tank with its lower end positioned around the periphery of the discharge opening 10 and its upper edge in contact with the side walls of the tank, so that a space 17 is left around the grid 16 to receive the deactivated water.

The tank 2 is adapted to be filled for the major portion of its height with finely di-

vided steel chips or turnings or other finely divided or crushed corrodible metal having an affinity for the dissolved oxygen in the water, as at 18.

Preferably a length of chain, or other flexible member 19, having a plurality of metal disks 20 thereon, will be mounted centrally in the body of material 18 so that when it is desired to discharge such material the central portion of the body may be disturbed or broken up by moving the chain 19 upwardly therethrough.

The water to be deactivated is adapted to flow from a feed pipe 21 through a branch 22 into a heater indicated at 23, thence through a pipe 24 into the upper end of the tank 2. The water will flow or seep down through the body of metal 18 and through the grid 16 into the space 17, from which it may be withdrawn through the outlet pipe 25, or, if no water is being withdrawn, it will pass out through the recirculating pipe 26 which connects with the branch pipe 22 leading to the heater.

A valve 27 is provided in the pipe 26 to permit the closing of this pipe, if desired, and a check-valve 28 is also provided in the pipe 26 to prevent the feed water entering the space 17 direct.

A drain 29 is provided in the bottom 4 of the tank to permit the draining of the tank when desired.

After the metal 18 has become spent or corroded beyond the point of efficiency, it is desirable to remove the same and, in order to do this, the hinged plate 12 is opened which will permit the metal to discharge by gravity. If, as is sometimes the case, the metal 18 is corroded so as to form a more or less spongy mass or unit so that it will not fall out of the tank, the manhole cover or plate 6 is opened and the chain 19 moved upwardly so as to disturb and break up the center of the mass of metal and permit it to be readily discharged.

After the spent metal is discharged, the bottom closure 12 is replaced, the tank is refilled with a new charge of metal, and the manhole cover 6 is replaced, again placing the apparatus in condition for use.

In some cases it may be found necessary to

first pass the feed water through a tank of magnesia, (not shown) so as to increase its alkalinity and coagulate the rust and cause it to adhere to the deactivating metal rather than to be carried over in a more or less colloidal form.

In other cases a sand filter may be necessary to remove the rust from the deactivated water. However, since the use of such filters are well known in combination with deactivating apparatus, they are not shown in this application.

While I have shown and described one specific embodiment of my invention, it will be understood that I do not wish to be limited thereto since various modifications may be made without departing from the scope of my invention as defined in the appended claims. The water may be passed through the heater and upwards through the scrap metal in the deactivating tank 2 when desired by making suitable changes in the arrangement of the valves and piping, and other modifications may be made.

25 I claim—

1. A water deactivating apparatus comprising a tank having an inlet opening at one end for the admission of the deactivating material and an outlet opening at the other end for the discharge of the used deactivating material, removable closures for said openings, a frusto-conical grid in the discharge end of said tank, said grid having its smaller end open and communicating with said outlet opening of said tank and having the peripheral edge of its larger end engaged with the side walls of said tank, thereby leaving a space between the side walls of said grid and said tank for the collection of deactivated water, an inlet at one end of said tank for water to be deactivated, and an outlet for the deactivated water at the other end of said tank and communicating with the space between the side walls of said grid and said tank.

45 2. A water deactivating apparatus comprising a tank having an inlet opening at one end for the admission of the deactivating material and an outlet opening at the other end for the discharge of the used deactivating material, removable closures for said openings, a frusto-conical sectional grid in the discharge end of said tank, said grid having its smaller end open and communicating with said outlet opening of said tank and having the peripheral edge of its larger end engaged with the side walls of said tank, thereby leaving a space between the side walls of said grid and said tank for the collection of deactivated water, an inlet at one end of said tank for water to be deactivated, and an outlet for the deactivated water at the other end of said tank and communicating with the space between the side walls of said grid and said tank.

60 3. A water deactivating apparatus com-

prising a tank having an inlet opening at one end for the admission of the deactivating material and an outlet opening at the other end for the discharge of the used deactivating material, removable closures for said openings, a frusto-conical grid in the discharge end of 65 said tank, said grid having its smaller end open and communicating with said outlet opening of said tank and having the peripheral edge of its larger end engaged with the side walls of said tank, thereby leaving a space between the side walls of said grid and said tank for the collection of deactivated water, a body of finely divided deactivating material filling the major portion of said tank above said grid, a flexible disturbing element 70 mounted centrally in said body of deactivating material and adapted to be moved out of said material prior to the discharge of said material so as to disturb or loosen said material and facilitate its discharge, an inlet at 75 one end of said tank for water to be deactivated, and an outlet for the deactivated water at the other end of said tank and communicating with the space between the side walls of said grid and said tank.

4. A water deactivating apparatus comprising a vertical tank having an inlet opening in its upper end for the admission of the deactivating metal and an outlet opening in its lower end for the discharge of the used and spent deactivating metal, removable closures for said openings, a frusto-conical sectional grid in the lower end of said tank, said grid having its lower end open and communicating with said outlet opening of said tank and having the peripheral edge of its upper end engaged with the side walls of said tank, thereby leaving a space between the side walls of said grid and said tank for the collection of deactivated water, a body of finely divided and fractured ferrous metal filling the major portion of said tank above said grid, a flexible disturbing member mounted centrally in said body of metal and provided with transverse disks at spaced intervals adapted to extend into said body of metal, said disturbing member being adapted to be moved upwardly out of said metal prior to the discharge of said metal so as to loosen said metal and facilitate its discharge, an inlet at the upper end of said tank for the water to be deactivated, and an outlet for the deactivated water at the lower end of said tank and communicating with the space between the side walls of said grid and said tank.

5. A water deactivating apparatus comprising a tank having an inlet opening at one end for the admission of the deactivating material and an outlet opening at the other end for the discharge of the used deactivating material, removable closures for said openings, a grid member positioned in the discharge end of said tank and spaced from the bottom and

side walls of said tank over at least a portion of its area to form a space for the collection of deactivated water, an inlet for the water to be deactivated adjacent the end of said tank opposite the end in which said grid member is positioned, and an outlet for the deactivated water at the other end of said tank and

communicating with the space between said grid and said tank in which the deactivated water collects.

10

In testimony whereof, I have hereunto signed my name.

FRANK N. SPELLER.
